DESIGN FOR A LIPSTICK HOLDER

Louis A. Samstag, New York, N. Y., assignor to Elizabeth Arden Sales Corporation, New York,
N. Y., a corporation of New York

Application March 18, 1937, Serial No. 68,260

Term of patent 7 years

To all whom it may concern:

Be it known that I, Louis A. Samstag, a citizen of the United States, residing in New York, county and State of New York, have invented a new, original, and ornamental Design for a Lipstick Holder of which the following is a specification, reference being had to the accompanying drawing, forming part thereof:

holder showing my new design on a slightly smaller scale;

I claim:

The ornamental design for a lipstick holder as shown.

LOUIS A. SAMSTAG.
